UNITED STATES PATENT OFFICE.

JOSEPH F. BIGGS, OF RICHMOND, VIRGINIA.

DESIGN FOR A TALKING-MACHINE CABINET.

Application filed October 26, 1921. Serial No. 510,683. Term of patent 14 years.

To all whom it may concern:

Be it known that JOSEPH F. BIGGS, a citizen of the United States, residing at the city of Richmond and State of Virginia, has invented a new, original, and ornamental Design for a Talking-Machine Cabinet, of which the following is a specification, reference being had to the accompanying drawing, forming part thereof.

In the drawings a perspective view of a

talking machine cabinet is illustrated showing the new design.

What is claimed is:

The ornamental design for a talking machine cabinet, as shown.

JOSEPH F. BIGGS.

Witnesses:

C. QUINN,
REITH M. BROOKING.
